UNITED STATES PATENT OFFICE.

GEORGE H. ROLFES, OF ST. LOUIS, MISSOURI, ASSIGNOR TO HANDLAN-BUCK MANUFACTURING COMPANY, A CORPORATION OF MISSOURI.

LANTERN-BURNER.

1,276,417.

Specification of Letters Patent. Patented Aug. 20, 1918.

Application filed May 11, 1918. Serial No. 233,994.

To all whom it may concern:

Be it known that I, GEORGE H. ROLFES, a citizen of the United States of America, a resident of the city of St. Louis, in the 5 State of Missouri, have invented certain new and useful Improvements in Lantern-Burners, of which the following is a full, clear, and exact description, reference being had to the accompanying drawings, forming a 10 part of this specification.

My invention relates to a burner intended for use more especially in railway hand lanterns which are subjected to severe motion in giving signals. The invention has 15 for its object the production of a flame spreading burner for a lantern of this kind so formed as to avoid extinction of the flame, due to currents of air entering the lantern. The flame spreader surrounds and surmounts 20 the upper end of the wick tube, with provision therein for the entrance of air to supply oxygen to a flame burning from the wick and means for so protecting the air entrance-ways as to avoid movement of air there- 25 through with sufficient force to interfere with the burning of the flame.

Figure I is a top view of my burner in position upon a lantern font.

Fig. II is a side elevation of the lamp font, the burner being partly in elevation and partly in vertical longitudinal section.

Fig. III is an elevation of the upper portion of the lamp font, the burner being partly in elevation and partly in cross section.

In the drawings A designates a lamp font of any ordinary form and B a burner fitted to said font. The burner includes a wick tube b within which is a wick C, preferably, though not necessarily, circular in cross section.

At the upper end of the wick tube of my burner is a cup-shaped flame spreader D, which comprises a bottom member 1 secured 45 to the tube, end walls 2 and side walls 3, the side walls being preferably longer than the end walls, thereby rendering the cup-shaped spreader of elongated shape. In the side walls of the spreader are apertures 4, preferably of semi-circular shape, the apertures terminating in proximity to the top edges of said side walls and having their curved edges extending downwardly to points near the bottom of the spreader. The apertures 50 4 serve to admit air to the interior of the

spreader D in a lateral direction through its side walls to supply the necessary oxygen for the support of combustion immediately above the wick of the burner, notwithstanding the fact that the wick terminates at the 60 bottom of the spreader, which extends thereabove.

The spreader D acts to spread the flame, due to its extension above the height of the upper end of the burner wick, the flame being drawn to the walls 2 and 3 of the spreader, thereby enhancing the illuminating power of the flame above the spreader.

To avoid the passage of air currents through the apertures 4 of such force as will interfere with the steady burning of a flame within the flame spreader, I provide baffle wings 5. These baffle wings extend downwardly and outwardly from the top edges of the side walls 3 of the flame spreader, being inclined away from such walls so that air may pass beneath them and then upwardly to enter the interior of the flame spreader through the apertures 4. The baffle wings, flaring outwardly from the top of 80 the flame spreader as described, preferably extend downwardly to a horizontal line through the burner at a lower level than the bottoms of the apertures 4, and consequently 85 there is no opportunity for strong currents of air to pass in a horizontal course through the apertures 4, but, on the contrary, all air entering the spreader through said apertures must move in an upward course as it passes beneath the baffle wings, and such air, by 90 passage in an upward course, assists materially not only in supplying oxygen to the burner flame but also in maintaining a steady flame.

While I have described my burner as intended more especially for use in lanterns, it is obvious that it may be used to good advantage in lamps.

The baffle wings 5 of my burner are preferably provided with apertures 5' so located 100 as to permit the passage of a certain amount of air through the baffle wings when a lantern equipped with my burner is lowered suddenly in giving signals. Therefore, when a lantern is so moved, there can be no sudden rush of air through the apertures 4 in such quantity as to interfere with the proper burning of the flame within the flame spreader. For the purpose of stabilizing the baffle wings 5 so that they will not be bent 110

from their proper inclined positions, relative to the side walls of the flame spreader, I provide each baffle wing with a supporting leg 5^a suitably secured to the lower portion 5 of the burner.

I claim:

1. A burner of the character described comprising a wick tube, and a cup-shaped flame spreader secured to said wick tube, 10 said flame spreader having walls provided with apertures and baffle wings flaring downwardly and outwardly from the upper portions of the apertured walls.
2. A burner of the character described 15 comprising a wick tube and a cup-shaped flame spreader secured to said tube, the walls of said spreader having apertures therein and having secured thereto flaring baffle wings which extend downwardly from the

upper portions of said walls to points beneath the lower edges of the apertures. 20

3. A burner of the character described comprising a wick tube and a cup-shaped flame spreader secured to said tube, the 25 walls of said spreader having apertures of semi-circular shape therein and baffle wings flaring outwardly and downwardly from the upper portions of the apertured walls.

4. A burner of the character described comprising a wick tube, and a cup-shaped 30 flame spreader secured to said wick tube, said flame spreader having walls provided with apertures and perforated baffle wings flaring downwardly and outwardly from the upper portions of the apertured walls. 35

In testimony that I claim the foregoing I hereunto affix my signature.

GEO. H. ROLFES.
